BARREL CART

Douglas S. Shepherd, 166 Kenoza Ave., Haverhill, Mass.

Filed June 7, 1965, Ser. No. 85,607

Term of patent 14 years

(Cl. D14—3)

Fig. 1.

Fig. 2.

Fig. 4.

Fig. 3.

The receptacles shown in broken lines in FIG. 4 are included for illustrative purposes only.

I claim:

The ornamental design for a barrel cart, as shown and described.
